UNITED STATES PATENT OFFICE.

ERIC E. HALL, OF CHICAGO, ILLINOIS.

FASTENING STRIP.

Application filed April 28, 1922. Serial No. 557,101.

To all whom it may concern:

Be it known that I, ERIC E. HALL, a citizen of the United States, and a resident of Chicago, in the county of Cook and State 5 of Illinois, have invented certain new and useful Improvements in Fastening Strips, of which the following is a full, clear, and exact specification.

My invention is concerned with building 10 materials and is designed to produce a novel fastening strip that is capable of a variety of uses.

To illustrate my invention, I annex here- 15 to a sheet of drawings, in which the same reference characters are used to designate identical parts in all the figures, of which,

Fig. 1 is a perspective view of a portion 20 of a concrete floor having two of my fastening strips embedded in the surface thereof;

Figs. 2, 3 and 4 are a side elevation, cross section and top plan view, respectively, of the fastening strip shown in Fig. 1;

Fig. 5 is a view similar to Fig. 1, but 25 showing a different design of strip em- bedded in the floor so that its top surface is flush with the top of the floor;

Figs. 6, 7 and 8 are a side elevation, cross section, and top plan view, respectively, of the fastening strip shown in Fig. 5; and

Fig. 9 is a perspective view of a portion of 30 a concrete floor and ceiling showing my fastening strips embedded in the bottom of the concrete joists to furnish a means for securing the ceiling thereto.

In carrying out my invention, I employ 35 a central strip 10, preferably composed of soft wood, but which may be a fiber composition made up of sawdust and suitable binding material, or something of the same general character. These strips are either 40 cut or molded to the desired shape in cross section, the strips shown in Figs. 1 to 4 preferably being pentagonal in cross section, the upper portion of the strips being in the 45 form of a rectangle with an inverted equilateral triangle secured on the under side thereof. In the form shown in Figs. 5 to 9, inclusive, the strip 10 is in the form of an inverted equilateral triangle.

This fiber strip is surrounded by a 50 metallic sheathing 11, which is preferably formed from a strip of sheet metal, which strip is preferably perforated, preferably by expanding two sections, 12 and 13, there- 55 of, in the customary manner of making expanded metal. Where the cross section

of the strip 10 shown in Figs. 1 to 4 is employed, the strip may be considered as made up of six sections 14, 15, 16, 17, 18 and 19, the sections 14 to 18 forming the five 60 sides of the completed strip, while the section 19 forms the anchoring insert, and the apertured portion 12 is in the portion 16, as that is the uppermost, and the apertures are employed to permit flooring to be nailed 65 onto the strips when they are employed as shown in Fig. 1 or in Fig. 5. The apertured or expanded portion 13 is located in the portion 19, the apertures being employed so that the concrete of the floor 20 will 70 pass through the apertures and anchor the strips in place when the concrete has hardened. To secure the sheathing in place, I form on the free edge of the portion 14 the series of tongues 21, which pass through 75 corresponding apertures 22 formed in the strip at the junction of the parts 18 and 19, and are pressed into engagement with the adjacent surfaces, as seen in Figs. 2 80 and 6.

The form shown in Figs. 1 to 4 is employed where it is desired to secure the wooden flooring (not shown) a short distance above the concrete floor 20, and in this case, as soon as the concrete floor 20 85 is poured and before it has time to harden materially, the strips are put into place, which can be readily done by shoving them back and forth on the floor with the portion 19 vertical until they have been worked 90 down so that the angles between the parts 14 and 15 and 17 and 18 are at the surface of the floor. Where the wooden flooring is to be secured directly on top of the concrete floor 20, as in Fig. 5, the shallower strips are forced into place in the same manner until their horizontal surfaces are flush with the surface of the poured concrete, as shown in Fig. 5. Of course it will 95 be understood that when the wooden floor- 100 ing is put in place, it is secured by nailing through the wooden flooring and the apertures 12 into the wooden or fibrous strip 10, and the flooring is secured in place more permanently than it would be with ordi- 105

nary strips, for the reason that the nails, as indicated in dotted lines in Fig. 1, will strike the angular metallic bottom of the strips and be bent over so as to clinch them to the strips, so that they cannot be accidentally pulled out or even readily pulled out intentionally.

In Fig. 9, I illustrate another use of the strips shown in Figs. 5 to 8, where they are placed in an inverted position on the wooden bottoms of the forms for the concrete joists 23 shown in connection with the concrete floor 20 of Fig. 9. When the concrete is poured and has hardened, and the forms are removed, the fastening strips are in place with the fastening sides inverted, so that the ceiling 24 can be nailed in place as indicated in Fig. 9.

While I have shown and described my invention as embodied in the form which I at present consider best adapted to carry out its purposes, it will be understood that it is capable of some modifications, and that I do not desire to be limited in the interpretation of the following claims except as may be necessitated by the state of the prior art.

20 What I claim as new, and desire to secure by Letters Patent of the United States, is:

1. As a new and useful article of manufacture, a strip of fibrous material enclosed on all sides thereof by a metallic sheathing, 25 said sheathing being provided with means for anchoring it in place.

2. As a new and useful article of manufacture, a strip of fibrous material enclosed on all sides thereof by a metallic sheathing, 30 said sheathing having projecting therefrom a perforated rib, for the purpose described.

3. As a new and useful article of manufacture, a strip of fibrous material enclosed by a metallic sheathing, said sheathing being 35 expanded on one face to form apertures.

4. As a new and useful article of manu-

facture, a strip of fibrous material enclosed on all sides thereof by a metallic sheathing, 40 said sheathing having projecting therefrom a perforated rib, for the purpose described.

5. As a new and useful article of manufacture, a strip of fibrous material enclosed by a metallic sheathing, said sheathing having projecting therefrom a rib, expanded to 45 form perforations therein, for the purpose described.

6. As a new and useful article of manufacture, a strip of fibrous material enclosed by a metallic sheathing, said sheathing being 50 formed of a sheet metal strip shaped with a plurality of angles, with connecting means for the edges at one angle, and an extension beyond said connected angle.

7. As a new and useful article of manufacture, a strip of fibrous material enclosed by a metallic sheathing, said sheathing being 55 formed of a sheet-metal strip shaped with a plurality of angles, a line of apertures in the strip at one angle and corresponding tongues formed on another edge to enter the apertures, and a perforated portion extending beyond said line of apertures.

8. As a new and useful article of manufacture, a strip of fibrous material enclosed on all sides thereof by a metallic sheathing, 60 said sheathing having projecting therefrom means for anchoring the same to a bed of plastic material.

In witness whereof, I have hereunto set my hand and affixed my seal, this 19th day 70 of April, A. D. 1922.

ERIC E. HALL. [L.S.]
